UNITED STATES PATENT OFFICE.

FREDERIC JOHN WHINCAP, OF GRAND RAPIDS, MICHIGAN, ASSIGNOR TO KIRSCH COMPANY, OF STURGIS, MICHIGAN, A CORPORATION OF MICHIGAN.

DESIGN FOR A MIDDLE ORNAMENT FOR DRAPERY-SUSPENSION FIXTURES.

Application filed December 17, 1928. Serial No. 29,313. Term of patent 3½ years.

To all whom it may concern:

Be it known that I, FREDERIC JOHN WHINCAP, a subject of the King of England, and a resident of Grand Rapids, county of Kent, and State of Michigan, have invented a new, original, and ornamental Design for a Middle Ornament for Drapery-Suspension Fixtures, of which the following is a specification, reference being had to the accompanying drawing, forming a part hereof, which is a front perspective view of the middle ornament for drapery suspension fixtures, showing my new design.

I claim:

The ornamental design for a middle ornament for drapery suspension fixtures as shown.

FREDERIC JOHN WHINCAP.
